(57) **CLAIM**

The ornamental design for a recordable car stereo, as shown and described.

DESCRIPTION

FIG. 1 is a front elevational view of the recordable car stereo of the present invention;

FIG. 2 is a left side elevational view of the recordable car stereo of FIG. 1;

FIG. 3 is a right side elevational view of the recordable car stereo of FIG. 1;

FIG. 4 is a top plan view of the recordable car stereo of FIG. 1; and,

FIG. 5 is a bottom plan view of the recordable car stereo of FIG. 1.

The broken lines showing of “recording” in FIG. 1 and the car stereo housing in FIGS. 2-5 are for illustrative purposes only and form no part of the claimed design.
